STEREOTYPE CASTING MACHINE

Filed Nov. 16, 1928

UNITED STATES PATENT OFFICE

RAY A. BROWN, OF ROCKFORD, ILLINOIS

STEREOTYPE-CASTING MACHINE

Application filed November 16, 1928. Serial No. 319,774.

This invention relates to stereotype casting machines of the kind especially adapted for use by small newspaper publishers and in jobbing and other printing shops for casting stereotype plates from matrices furnished by newspaper, advertising and other service agencies. The principles of my invention are, however, not limited to stereotype casting machines of this particular size or for this limited use but are generally applicable in the casting of stereotype plates.

One of the primary objects of my invention is to provide a generally improved and simplified stereotype casting machine of the character described which will be easy to operate and practical for the purposes intended.

I have also designed the machine so that it may be produced at a low cost and yet be so sturdily constructed as to be long lived and durable under all working conditions and requirements of a machine of this kind.

My invention contemplates the provision of a casting box and a metal melting pot constructed and mounted in a novel manner. The casting box, preferably in the form of an upper and a lower platen, the former of which may be swung to an open position to receive the matrice and gauges, is mounted upon a low frame so as to swing to and from a horizontally disposed work-receiving position and a vertically disposed casting position. While the casting box may be mounted in a number of ways it has been found advantageous to pivot it on the frame at a point intermediate its ends whereby it may be rotated from position to position with little effort. The melting pot preferably with a bottom pouring spout, is mounted upon a vertical standard and may be rotated between a normal heating position away from the casting box and a pouring position over the casting box. Since the melting pot moves substantially horizontally there is very little danger of spilling the molten metal. The pouring handle is equipped with a locking means to prevent accidental pouring while the handle is being used to move the melting pot from position to position. The supporting frame and standard is composed princi-

pally of pipe members whereby it may be made at low cost and yet be sturdy in construction.

Another object is to so construct the machine that it may be operated quickly and by a person not especially skilled in this class of work.

Other objects and attendant advantages will be appreciated by those skilled in this art as the invention becomes better understood by reference to the following description and the accompanying drawings.

Figure 1 is a front elevation of a stereotype casting machine embodying my invention showing in solid lines the normal position of the parts and in dotted lines the casting or metal-pouring position of the parts; and

Fig. 2 is a side elevation showing the casting box in the horizontally disposed position. In dotted lines the upper platen is shown raised to a work-receiving position.

The casting box may be of any preferred construction. In the present instance it is composed of an upper and a lower platen designated generally by 5 and 6. One end of the lower platen is equipped with lugs 7 to which the upper platen is connected by bolts at 8, so that it may be swung between an open and a closed position to permit of free access for placing the matrice and gauges. A latch 10 is provided to hold the upper platen firmly in its open position. The casting box is constructed for making either "type high" or "thin plate" castings. In making the type high castings the upper platen is attached with the bolts at 8 while in making thin plate castings the upper platen is attached with the bolts at 9. The latch 11, pivoted on the lower platen and sliding on a guide pin at 12 acts as a double stop, holding the casting box in either the horizontal or vertical position, a series of suitable clamps 13 serving to hold the platens firmly together during the casting operations. The casting box may be supported by any suitable means whereby it may be moved between a horizontally disposed work-receiving position and a vertically disposed casting position. I have here used a particular type of

construction which may be seen to offer distinct advantages. A vertical standard 14 is fitted at its bottom end with a connecting member 15 having sockets into which are set legs or feet 16 and a cross member 17. The cross member terminates in a second connecting member 18 which is supported by an upright 19 with a foot 20 at the base. Thus the frame consists of an upright having two stabilizing legs at its base and a single offset leg connected by a horizontal member. Trunnions 21 on the lower platen of the casting box are journaled in the two connecting members holding the casting box with its axis at right angles to the vertical member 14.

The melting pot generally designated by 22 rests in the cradle 23 which is rotatably mounted on the vertical upright 14 so as to be capable of being swung through an angle of 180° between a position convenient for heating and a pouring position as shown in Fig. 1. The side of the cradle bearing 26 is slotted at 24 to receive a pin 25 passing through the slot and set into the vertical upright to act as a stop and prevent the pot from being rotated beyond the position desired. The flow of metal is controlled from the lever 27 mounted upon the melting pot and connected to a plunger in the spout 28 by means of the link 29. The weight 30 is attached to cause the lever to return to the closed position when released. I have used a novel and positive means for preventing the lever 27 from being accidentally depressed, thus making it safely possible for this lever to serve also as a handle for rotating the melting pot from one position to the other. The latch handle 31 is attached to the handle of the pouring lever at 32 with a short end extending beyond the fulcrum. To this short end is attached the rod 33 which is forked at its lower end 34. When the latch is in the safety position the fork rests over the projection 35 from the cradle, so that the pouring lever may not be depressed. The dotted lines in Fig. 1 show the latch released and the lever ready for pouring.

The melting pot may be heated by any suitable means. I have shown here a gas burner generally designated by 36 supported on the melting pot cradle and supplied with gas through the flexible tube 37.

The operation of my improved casting machine is easy and convenient. Fig. 2 shows the normal starting position, with the casting box open and the melting pot being heated. In practice it is necessary for the operator to first cast a blank or slug to heat up the casting box. The blank is permitted to cool and returned to the melting pot. The operator should then arrange the matrices and gauges upon the lower platen in the usual manner, lower the upper platen, clamp it securely in place, and then shift the casting box from its horizontally disposed posi-

tion to the vertically disposed position for casting. It will be held firmly in this position by the latch. The melting pot should then be swung from its heating position to the pouring position over the vertically disposed casting box. The operator may then pour the casting by raising the latch and depressing the pouring lever. Reversing the operations will bring the machine back to its normal position. It will be evident that the operations may be very easily performed. The casting box may be easily swung from position to position because of its balanced mounting. The melting pot is simply rotated on its axis in a horizontal plane, very little effort being required for the operation. In addition no special skill is required of the operator to safely carry out the movements. It may also be seen that my improved machine is free from many structural defects found in prior machines which have proved to be a source of danger unless handled with care.

It is believed that the foregoing conveys a clear understanding of the objects prefaced above, and while I have illustrated but a single work embodiment, it should be understood that changes might be made in the construction and arrangement without departing from the spirit and scope of the invention.

I claim:

1. A stereotype casting machine comprising spaced vertical members and a connecting horizontal member; a casting box rotatably mounted at its center of gravity between said vertical members, having a lower platen and an upper platen pivotally attached thereto, a latch connecting said platens arranged to hold said upper platen in an open position, feet at the lower ends of the vertical members to maintain them in a vertical position, a melting pot mounted upon and adapted to rotate about one of the vertical members as an axis between a position convenient for heating and a position above the vertical casting box, convenient for pouring, and means for heating the melting pot.

2. A stereotype casting machine comprising a frame, a casting box, a vertical upright, a melting pot provided with a bottom-pouring mechanism mounted upon the upright, and adapted to rotate thereon, said mechanism being actuated by a lever, means for locking the pouring lever to permit the same to be used for rotating the melting pot without danger of accidental escape of molten metal, and means for heating the melting pot.

3. A stereotype casting machine comprising pipe members in the form of an inverted V, having a vertical pipe standard, a spaced vertically disposed pipe member, a connecting horizontally disposed pipe member, a casting box consisting of an upper platen and a lower platen, the lower platen having trun-

nions intermediate the ends, one journaled substantially at the apex of said V and one in said vertical member above the horizontal member and offset sufficiently to permit of 5 rotating the casting box about its center of gravity through an angle of substantially ninety degrees between a horizontally disposed work-receiving position and a vertically disposed metal-pouring position, feet at 10 the lower ends of said pipe members to maintain them in a vertical position, a bottom-pouring melting pot mounted upon and adapted to rotate about said pipe standard as an axis between a position convenient for 15 heating and a position above the vertical casting box convenient for pouring, and means for heating the melting pot.

4. A stereotype casting machine comprising a supporting frame consisting substantially of vertically and horizontally disposed pipe members including a pipe standard, a casting box adapted to move between a horizontally disposed work-receiving position and a vertically disposed metal-pouring position, 20 a bottom-pouring melting pot, a cradle for holding and supporting said melting pot mounted upon and adapted to rotate horizontally about said pipe standard as an axis between a position convenient for heating and a 25 position above the vertical casting box convenient for pouring, means for limiting the rotation of said cradle between said heating and said pouring position, and means for heating the melting pot mounted upon said 30 vertical member below the heating position of the melting pot.

In witness of the foregoing I affix my signature.
